[57] CLAIM

The ornamental design for an electronic control module, as shown and described.

DESCRIPTION

The electronic control module mimics a fluorescence response of a reacted test strip and checks functional aspects of a meter.

FIG. 1 is a top perspective view of an electronic control module showing my new design;

FIG. 2 is a bottom perspective view thereof;

FIG. 3 is a top plan view thereof;

FIG. 4 is a right elevational view, the left elevational view being a mirror image thereof; and,

FIG. 5 is a rear elevational view thereof.
